UNITED STATES PATENT OFFICE.

FREDERICK J. LENZ, OF MINNEAPOLIS, MINNESOTA.

VALVE-CASING CAP.

Application filed January 21, 1920. Serial No. 353,003.

To all whom it may concern:

Be it known that I, FREDERICK J. LENZ, a citizen of the United States, residing at Minneapolis, in the county of Hennepin and 5 State of Minnesota, have invented certain new and useful Improvements in Valve-Casing Caps, of which the following is a specification.

This invention relates to faucets and the 10 objects of my improvements thereon, are first, to provide a faucet having its various elements so arranged that they may be easily assembled and disassembled; second, to provide a cone shaped valve having its small end 15 provided with a port which communicates with a transverse port for a purpose to be hereinafter more fully brought out; third, to provide a durable and lasting faucet which requires no washers and will compensate 20 for the contraction and expansion of the faucet and fourthly to provide a cap provided with a cone shaped inwardly extending pinte 25 within its seat in a manner to be hereinafter described.

With these and other features of novelty whereby my invention is characterized will be hereinafter pointed out with particularity 30 in the claims, but for a full understanding of my invention and its various objects and advantages, reference may be had to the following detailed description taken in connection with the accompanying drawings, 35 wherein:

Figure 1 is a vertical longitudinal section taken through the first modification of my faucet.

Figure 2 is a vertical longitudinal section 40 taken through the second modification of my faucet.

Figure 3 is a vertical longitudinal section taken through the third modification of my faucet, and

45 Figure 4 is a side elevation of the faucet shown in Figure 3.

By referring to the accompanying drawings, it will be seen that the modifications disclosed in Figure 1 relate particularly to a 50 shampoo faucet and consists of the base 1 having the two inlet pipes 2. These inlet pipes 2 are provided with the ports 2' which lead into the conical shaped valve seat 4 which in turn leads into the body of the faucet 3 so that the water may pass therefrom through the outlet spout 13 over which

a hose is adapted to be received. I shall just refer to the valve mechanism to the right of the faucet but it will of course be understood that the mechanism to the left is an 60 exact duplicate thereof.

In the valve seat 4 there is situated the valve 10 which has the longitudinal opening 11 which opens through the small end of the conical shaped valve 10 so as to communicate with the portion 3 of the faucet. A transverse opening 12 is provided in the valve 10 so as to communicate with the port 2' when the valve stem 14 is turned by means of the handle 15. Integrally extending from 70 the valve seat 4 there is provided the neck 5 which is threaded at 6 to receive the cap 7 which is also threaded at 6 and is provided with the integrally extending pinte 8 which is conical shaped and provided with a bore 75 through which passes the stem 14. This conical shaped pinte 8 is adapted to receive the conical shaped coil spring 9 so as to protect the same from the wear which would be occasioned by the rotation of the 80 stem 14 and at the same time to force the valve 10 tightly within the valve seat 4. It will also be seen that by having the pinte 85 conical shaped that the mechanism may be easily and quickly assembled by placing the coil spring over the stem 14 and afterwards threading the cap 7 over the neck 5 whereby the pinte 8 will easily pass into the coil spring because of its conical shape.

By referring to Figure 2 it will be seen 90 that I have disclosed a faucet of the ordinary construction consisting of the inlet pipe 20 which is provided with an integral wall guard and the threaded portion 23. A spout 24 is provided for the outlet and is 95 curved downwardly as is the usual form. The valve 10 is of the same construction as the modification just described and is situated in the conical valve seat 4 which is provided with the neck 5 threaded at 6 for 100 receiving the cap 7 which in turn has the conical shaped pinte 8 for receiving the springs 9. The valve 10 has the usual stem 14 for receiving the handle 15 for rotating the same. It will be seen that the water will 105 pass through the pipe 20 into the opening 12 and through the longitudinal bore 11 into the spout 24.

The modification shown in Figures 3 and 4 is adapted to be used in bath tubs whereby 110 the hot and cold water may be passed through a single outlet 27 so as to have the

temperature thereof as desired. The inlets 29 are provided with guards and the threaded portion 30 upon which is situated the lock nut 31. In between the valve portions 5 there is also provided the soap container 28 which is situated above the body portion 26 of the faucet. The valve mechanism to the left and right are duplicates of the valve mechanism described for Figure 2 and it 10 will be seen that the water passes through the pipes 29 into the transverse opening 12 of the valve 10 and passes through the longitudinal bore and port 11 into the body 26 and out through the spout 27.

15 I have above described three modifications of my invention in each of which it will be seen that I have used the conical shaped valve 10 to advantage and I have also provided the cap 7 having the conical spindle 20 8 for receiving the coil spring 9, each modification having the advantage of being easily assembled and disassembled. In each modification it will be seen that the water enters the valve through the transverse 25 opening or in other words hits the valve at right angles so that in assembling or renewing the spring 9 if such would ever become necessary it would probably not be necessary to shut the water off at the main 30 valve of the system for the valve itself would have a tendency to stay within the valve seat 4. In the modification shown in Figure 2 it will be readily seen that considerable pressure would be necessary to overcome this 35 tendency of the valve to stay within its valve seat and even in the modifications disclosed in Figures 1 and 3 it will be seen that this tendency of the valve to stay within its valve seat would overcome such pressure as 40 would be caused by the water in the system after the main valve of the system had been shut off and in all of the modifications this valve could be easily held in place by the operator while removing the cap and spring.

45 I wish it understood that the above are the

preferred forms of use of this valve mechanism but I wish it understood that I may make such changes in construction, combination and arrangement of parts as will fall within the scope of the appended claims. 50

Having thus described my invention, what I claim as new is:—

1. In a valve, a casing having a conical shaped bore communicating with an inlet and an outlet, a conical cup-shaped valve mounted in the bore of the casing, a stem extending from the valve through the casing, a cap for the casing including a flat disk having a central aperture, an annular threaded flange extending at right angles to the cap for engagement with the casing, a centrally located and integrally extending conical shaped pintle provided upon said cap and having a longitudinal bore extending parallel to said flange and registering with said opening, said stem extending through the bore of said pintle, and a conical shaped coil spring disposed about said pintle and bearing against the valve for holding it in the bore of the casing, said pintle providing a relatively long bearing for said stem and also providing a guide for said spring. 65

2. As a new article of manufacture, a flat disk shaped cap having a centrally located 70 aperture, an annular threaded flange extending at right angles to the cap, a centrally located and integrally extending conical shaped pintle provided upon said cap and having a longitudinal bore extending 75 parallel to said flange registering with the opening in said cap, said pintle terminating substantially coplanar with the end of the flange.

In testimony whereof I affix my signature 80 in presence of two witnesses.

FREDERICK J. LENZ.

Witnesses:

AUGUST W. LENZ,
IVER SUNDBY.
